RACK FOR PRE-TIED NECKTIES

John H. Otteman, 6768 Cord Ave., Pico Rivera, Calif.

Filed Aug. 27, 1963, Ser. No. 76,374

Term of patent 14 years

(Cl. D33—8)

I claim:

The ornamental design for a rack for pre-tied neckties, as shown.
